US00D599676S

(12) **United States Design Patent**
Friebe et al.

(10) **Patent No.:** **US D599,676 S**
(45) **Date of Patent:** **** Sep. 8, 2009**

(54) **FOIL PACKAGE**

(75) Inventors: **Joachim Friebe**, Heimertingen (DE);
Andreas Michalsky, Memmingen (DE);
Maurice Habram, Kempten (DE);
Agata Surdziel, Kempten (DE); **Peter Ganz**, Untrasried (DE)

CLAIM

The ornamental design for a foil package, as shown and described.

DESCRIPTION

FIG. 1 is a front side perspective view of a foil package showing our new design;

FIG. 2 is a right side perspective view thereof;

FIG. 3 is a bottom view thereof;

FIG. 4 is a front view thereof;

FIG. 5 is a perspective view thereof; and,

FIG. 6 is a top view thereof.

The broken line portions of the foil package are for illustrative purposes only and are not intended to limit the claimed design to the features shown in broken lines.
